CONTINUOUS LOW TEMPERATURE PROCESS AND APPARATUS FOR TREATING HYDROCARBONS

Filed Nov. 24, 1923

UNITED STATES PATENT OFFICE

WILLIAM L. GOMORY, OF CHICAGO, ILLINOIS, ASSIGNOR TO STANDARD OIL DEVELOPMENT COMPANY, A CORPORATION OF DELAWARE

CONTINUOUS LOW-TEMPERATURE PROCESS AND APPARATUS FOR TREATING HYDRO-CARBONS

Application filed November 24, 1923, Serial No. 676,760, and in Hungary August 1, 1923.

The subject-matter of my previous applications, Serial Nos. 498,670, 557,040, and 616,156 of which this application is a continuation in part, is a process and apparatus 5 for decomposing heavy hydrocarbons into lighter hydrocarbons characterized by the fact that the heating, decomposing and vaporizing occur in three distinctly separate steps. The first step, the heating, is 10 accomplished in such a manner that the crude material is rapidly heated under pressure in liquid form to a predetermined temperature, but without any substantial decomposition. There is no carbon deposition 15 in the heating zone, thereby the continuity of the process is not impaired. The crude material, leaving the heating zone with a predetermined temperature, passes into the cracking zone where it remains under the 20 same temperature and pressure for a length of time necessary to obtain a thorough decomposition and the deposition of carbon. The properly decomposed material passes into a vaporizing chamber and can be treated 25 in any convenient manner according to the description of my previous applications, Serial Nos. 498,670, 557,040, and 616,156. The heating can be accomplished, for instance, in a coil set in a furnace. The de- 30 composition occurs in the cracking zone, consisting of one or more cracking chambers (converters) which are provided with the necessary appliances for the maintenance of the proper temperatures and pressures. 35 The distillation of the decomposed oil can be carried out with or without the use of a cooler which is interposed between the vaporizer and cracking chambers.

The subject-matter of this present application 40 is a specific improvement in connection with the cracking zone (converters) and its operation. The present process and apparatus enables periodic removal of carbon from any one of the converters without 45 disturbing the continuity of the operation and furthermore makes it possible to obtain commercial results at very much lower temperatures than used by other methods.

In the accompanying drawings Fig. 1 is 50 a diagrammatic illustration of the system.

Fig. 2 is a diagrammatic illustration of the heating zone; and

Fig. 3 is a diagrammatic illustration of a means for heating a converting chamber.

The details of the heating zone and the necessary cooling apparatus are not shown on Fig. 1, which is a diagrammatic illustration of the cracking zone only in connection with the vaporizer. The drawing shows five cracking or decomposing chambers (converters) each of which is provided with appliances which are necessary for the maintenance of the proper temperature and pressure. These appliances are well known in the industry and are not shown in Fig. 1. The heating of the cracking chambers for maintaining the cracking temperature can be accomplished either by heating the tanks on the outside, or inside, with fire tubes, for instance, but preferably in such a manner that the temperature of the heating agent is kept close to the temperature of the oil, so that an overheating of the cracking chamber or fire tubes is avoided. This can be achieved for instance by rapidly circulating flue gases of proper temperature around the tank or through the fire tubes in any known manner.

As shown, for example, in Fig. 2, 5 is a furnace heated by burner 40, and within which is a coil 6 into which oil is forced, preferably through a heat interchanger 9, by pressure pump 7. The heated oil passes out of the coil into pipe line I of Fig. 1. The cracking or decomposition chambers are heated in any suitable manner, e. g. as shown in Fig. 3, by a burner 41, or by hot waste gases, a series of baffles 27 forming an encircling flue terminating in stack 28. Oil is introduced through pipe a' (see Fig. 1) and flows out through pipe b'. H' is a valved exit pipe (see Fig. 1), for releasing vapors during the filling of the chamber, the valve being closed at other times. The setting of the chambers is so arranged that their bottoms or sides up to a certain height are bricked in to prevent direct impingement of heat on that portion of the shell within which carbon deposits.

The series of cracking chambers (con-

verters) is connected with a heating zone at one end and with the vaporizer at the other end. Further, the cracking chambers are inter-connected in such a manner that it is possible to connect in or cut out any one of the converters from the system without disturbing the same. Another pipe line serves to charge the cracking chambers with pre-heated oil. The vapors which might develop while the cracking chambers are being charged can escape through the properly set relief valves and their connections, communicating through a cooler with a receiving tank.

15 The high pressure pump forces the crude material through the heating zone into the main line No. I, from which through properly valved connection the hot crude material can be directed through any of the converters. Through line No. IV any one of the converters can be periodically charged with pre-heated crude material. Line No. II, with its valved branches, establishes connection among the converters and renders it possible to cut out any one of the converters and connect in any other converter without disturbing the continuity of the operation. No. III line continuously carries the decomposed material from any one of the converters through a reducing valve to vaporizer J and through line No. V the decomposed material can pass from any one of the converters which has been cut out for cleaning, through a reducing valve into the vaporizer J.

40 The heated crude material coming from the heating zone into the main line No. I can pass through branches a^1 — a^5 into F^1 — F^5 (converters) preferably on or close to their bottoms. Branch-lines b^1 — b^5 carry away the material from the top of the converters thereby keeping them substantially full with oil.

45 As an example of the operation of the process, let it be assumed that F^1 , F^2 , F^3 and F^4 converters are in operation and F^5 will have to be cut out for cleaning, while F^5 which has been previously cleaned is ready to be connected into the system.

50 The crude material, which has been heated to the predetermined decomposing temperature during its rapid passage through the heating coil, continuously passes through main-line I and valves 11 and 21 (valves 11' and 71 are closed) through a^1 branch-line and 31 check valve (valve 91 is closed) into F^1 converter and therefrom through b^1 branch-line and valves 41 and 51 (valves 81 and 61 being closed) into return-line II from which it passes through valves 72 and 22, (valves 62 and 12 are closed) through a^2 branch-line and 32 check valve (valve 92 being closed) into F^2 converter; from F^2 converter through b^2 branch-line and valves 42 and 52 (valves 82

and 62 being closed) into return-line II from which it passes through valves 73 and 23, (valves 63 and 13 are closed) through a^3 branch-line and 33 check valve (valve 93 being closed) into F^3 converter; passing through F^3 converter the material travels through b^3 branch-line and valves 43 and 53 (valves 83 and 63 being closed) into return-line II, and therefrom through valves 74 and 24 (valves 64 and 14 are closed) through a^4 branch-line and 34 check valve (valve 94 being closed) into F^4 converter. The cracked material, after passing through F^4 converter goes through b^4 branch-line and valves 44 and 84 (valves 54 and 84' being closed) arriving into transfer-line III, through which, passing valve 85' (valve 85 being closed) then (either through cooler J' or by-passing cooler J') through reducing valve G into vaporizer J. In this way the heated material arising from the heating coil passed through converters F^1 , F^2 , F^3 and F^4 in series and was decomposed to the desired degree during this passage and the properly decomposed oil—by-passing F^5 converter—reaches the vaporizer.

55 The next step in the operation is to cut out F^4 converter from the system for cleaning, respectively to prepare F^5 converter to be connected into the system. For this purpose—without disturbing the operation of the plant with F^1 — F^4 converters, F^5 converter will be charged through charging-line IV and valve 105 (valves 101, 102, 103 and 104 are closed) with crude material, pre-heated by passing it through any convenient preheater under pressure. Of course, the air from F^5 converter must have been previously displaced. The vapors which might evolve during the charging of F^5 converter can escape through H^5 relief valve and relief line and passing through cooler U into relief tank W.

60 After converter F^5 is filled I can proceed to cut out F^4 converter from the system. To maintain the continuity of the process, first of all, valve 64 is opened, valves 74, 24, 84 and 44 are closed, then valve 94 is opened and thereby the decomposed material will pass through discharge-line V and reducing valve 100 into vaporizer J.

65 Simultaneously with the discharging of the decomposed material from F^4 converter, F^5 converter, which has been previously filled with preheated material, is connected into the system by opening valves 75, 25, 45, and 85 and closing valve 85', so that the material leaving F^5 converter through b^5 branch-line and valves 43 and 53 will pass through return-line II (valves 63, 65, 83, 74 and 54 being closed) through valves 75 and 25 (valve 15 is closed) through a^5 branch-line and 35 check valve (valve 95 being closed) into F^5 converter and through it and b^5 branch-line, passing valves 45 and

85 (valves 55 and 85' being closed) into and through transfer-line III into vaporizer J.

With this arrangement the apparatus is continuously operating with full capacity 5 without any interruption. The continuity of operation of the heating zone is assured by avoiding any carbon deposition in same, as there is no decomposition in the coil. The continuity of the distillation from the 10 vaporizer, while the cleaned converter is being connected into the system and properly operating, is assured by the decomposed material discharged from the converter which has been cut out from the system for cleaning.

The cutting out of any other converter of the system for cleaning purposes occurs identically with the above proceeding; naturally the cleaned converter is always 20 to be filled with preheated material before the converter which is to be cleaned is cut out from the system.

Preferably the cleaned converter already filled with preheated material should be 25 connected into the system as the first or the last member of the series of converters in regard to the direction of the oil travel through the system. If the converter, which has just been charged with preheated material and connected into the system, is so connected that it is the last member of the series, then the decomposed material arising from the previous converters with the decomposing temperature will have to pass 30 through the preheated material contained in that last converter and necessarily of a lower temperature than the incoming decomposed oil. The forced passage of the incoming high temperature decomposed oil 40 through the large body of lower temperature material is very advantageous as it delays the vaporization of the light hydrocarbons contained in the incoming decomposed material by reabsorbing them and thereby stabilizing them.

Beside the advantages already cited above, the present process and apparatus has the following advantages.

The exceedingly long time which the crude 50 material has to spend in this process under optimum cracking conditions enables the decomposition to be carried out gradually and at lower temperatures than used by other processes, that is the exceedingly 55 high temperatures which have disadvantageous effect on the products is substituted by considerably prolonging the time of reaction. In other words, instead of heating the oil to a temperature of 460° C. for a 60 short while to produce a certain amount of gasoline, in this process the time element is sufficiently prolonged to enable to obtain the same or better results from the same crude material with materially lower 65 temperatures, for instance, with 395° to 400° C.

The importance of the lower temperature is obvious for both process and apparatus. The exceedingly high temperatures used by other processes wear out the equipment very rapidly, consequently by decreasing the reaction temperature the life of the equipment is being prolonged. The decomposing temperature which is being used in any process has a very decided influence on the quality of the gasoline produced, that is, with a slow 70 decomposition carried out at lower temperatures the quality of the produced gasoline is far superior (less unsaturated hydrocarbons) than with rapid decomposition carried out at exceedingly high temperatures. 75 The low temperature decomposition is more economic as less permanent gas is produced and the carbon (coke) is of a softer and looser consistency and does not adhere to the walls of the converters.

For the charging of the cleaned converters to be connected into the system the same crude material can be used which arrives from the heating coil. In other instances it is preferable to use a different material for 80 this purpose.

The number of converters to be used naturally can be larger or smaller than five and the method of connecting in and cutting out, as well as the nature of the pipe-lines 85 and connections can vary in wide limits, without departing from the spirit of my invention.

What I claim is:

1. A continuous low temperature process 100 for cracking heavy hydrocarbons into lighter hydrocarbons which comprises heating the raw material to a predetermined decomposing temperature while rapidly forced under pressure through a heating coil at such rate 105 that no substantial decomposition occurs and then continuously passing the heated oil through a series of decomposing chambers, without distillation, while the temperature and pressure are maintained, cutting out 110 from the system any intermediate one of the series of decomposing chambers for cleaning and reconnecting it into the system after it has been cleaned, each while continuing the chambers on each side of said intermediate chamber in normal series operation.

2. A continuous low temperature process 115 for cracking heavy hydrocarbons into lighter hydrocarbons which comprises heating the raw material to a predetermined decomposing 120 temperature while rapidly forced under pressure through a heating coil at such rate that no substantial decomposition occurs and then continuously passing the heated oil through a series of decomposing chambers, without distillation, while the temperature and pressure are maintained, cutting out 125 from the system any one of the series of decomposing chambers for cleaning, and charging the cleaned chamber with raw ma- 130

terial, and reconnecting it into the system after it has been cleaned, without disturbing the continuity of the process.

3. A continuous process as claimed in claim 2, in which the chamber charged with raw material is connected into the system as the last member of the series of decomposing chambers so that the decomposed material continuously passing through the system at the decomposing temperatures passes through the lower temperature charge of the newly connected converter and then discharging the decomposed material at reduced pressure into a vaporizing chamber.

4. A continuous process as claimed in claim 2 in which simultaneously with the disconnection of a decomposing chamber for cleaning, another clean decomposing chamber charged with raw material is connected into the system without disturbing the continuity of the process.

5. A process as claimed in claim 2 in which the clean converter is charged with raw material different from that continuously passing through the system.

6. An apparatus for cracking hydrocarbons comprising a plurality of cracking chambers connected in series and means for delivering heated oil under pressure to and in succession through said chambers, a vaporizing chamber to which the series of cracking chambers is connected, means for maintaining the temperature and pressure, and means including the necessary pipe connections and valves for charging and connection or disconnection of any one of the chambers forming a part of said series into and from the system while maintaining series flow through all of the remaining chambers in said series.

7. An apparatus for cracking hydrocarbons, a plurality of cracking chambers, a series connecting manifold, connections between each of said chambers and said series connecting manifold whereby oil may be caused to flow in series through said chambers, means for charging heated oil into the first of said chambers to flow therethrough in series, means for discharging oil from the last of said chambers in series, a separate discharge manifold, and means for disconnecting an individual one of said chambers from the series connecting manifold and discharging the disconnected chamber through said discharge manifold.

8. In apparatus for cracking hydrocarbons, a plurality of cracking chambers, a loop conduit forming a series connecting manifold, means for controllably connecting the individual cracking chambers with said manifold whereby oil may be flowed in series through said chambers with any one of said chambers as the starting point thereof, a charging manifold, controllable connections between the charging manifold and

said chambers whereby heated oil may be charged to any one of said chambers forming the initial one of the series, a discharge manifold, controllable means connecting said discharge manifold with each of said chambers whereby oil may be discharged from the last one of said series, an independent discharge manifold, and controllable means connecting said independent discharge manifold with each of said chambers whereby a disconnected one of said chambers may be separately discharged.

9. In apparatus for cracking hydrocarbons, a plurality of cracking chambers, a loop conduit forming a series connecting manifold, means for controllably connecting the individual cracking chambers with said manifold whereby oil may be flowed in series through said chambers with any one of said chambers as the starting point thereof, a charging manifold, controllable connections between the charging manifold and said chambers whereby heated oil may be charged to any one of said chambers forming the initial one of the series, a discharge manifold, and controllable means connecting said discharge manifold with each of said chambers whereby oil may be discharged from the last one of said series.
